UNITED STATES PATENT OFFICE.

JOHN A. HOLMQUIST, OF WOODLAWN, PENNSYLVANIA.

TAKE-UP REEL FOR WIRE-FENCE MACHINES.

1,378,956.

Specification of Letters Patent. Patented May 24, 1921.

Application filed March 22, 1920. Serial No. 367,705.

To all whom it may concern.

Be it known that I, JOHN A. HOLMQUIST, residing at Woodlawn, in the county of Beaver and State of Pennsylvania, a citizen 5 of the United States, have invented or discovered certain new and useful Improvements in Take-Up Reels for Wire-Fence Machines, of which improvements the following is a specification.

10 My invention relates to improvements in wire-fence machines; and, while in the accompanying drawings I show it applied to a machine of the Denning type (see Denning Patent No. 816,538, and also my companion 15 application, Serial No. 367,704), it will be understood that the invention is applicable to fence machinery generally, of whatever type. It has particularly to do with the reel for taking up the finished fence.

20 In the accompanying drawings, Figure I is a view in side elevation of a wire-fence machine having my invention applied to it; Fig. II is a view in plan and to larger scale of the reel of the machine of Fig. I, in which 25 reel as I have said my invention is found; Fig. III is a view in transverse section of the structure shown in Fig. II, the plane of section being indicated by the line III—III, Fig. II; and Fig. IV is a view in end elevation (the right-hand end, Fig. II). From 30 Fig. IV the guide roller and its supports are, for the sake of simplicity of showing, omitted.

It is characteristic of the Denning machine that in its operation strand-wire feed 35 and stay-wire feed are continuous, and the fence-forming instrumentalities perform their various functions under this all-dominating condition. I have so far modified the Denning machine that I have introduced into 40 it the take-up device of the Bates and Cocker Patent, No. 732,155, and in consequence imposed upon the strand wires as they pass through the coilers an intermittent movement, or at least a movement of periodically 45 variable speed. This is fully explained in my companion application, Serial No. 367,704. But, even so, the delivery of finished fence from the machine goes on continuously and at uniform rate, so long as 50 the machine is in operation; and this is characteristic of the typical Denning machine as well.

Referring to Fig. I of the drawings, the machine there shown in side elevation is 55 provided with a crimping drum 2, which seizes and crimps the otherwise finished

fence, and exerts upon the strand wires the tension which draws them through the machine. From the crimping drum the finished fence is delivered. The path of delivery of 60 the fence from the crimping drum 2 is indicated by the dotted line *a*, and the direction is indicated by arrow points.

I preferably so arrange the crimping drum and the feed of the fence to it that the finished fence is delivered at the top of the machine (ordinarily some eight feet from the floor) and in a direction forwardly, from the front of the machine. This is a reversal 65 in direction of delivery, from what is shown 70 in the Denning patent already alluded to, No. 816,538. The advantage of this change in arrangement is that the reel upon which the fence is coiled may then be arranged in front of the machine, at a convenient interval 75 behind the attendant who ordinarily stands facing the machine. And in such position the drum and the web of fence advancing to the reel are directly accessible by the attendant, and he need not leave his place 80 and walk around the machine to reach them.

Coming now to the particular construction of the reel, note is first of all to be made of the fact that it is provided with duplicate spools 20, 20, upon either of which the advancing web of fence may be wound. The web of fence as it comes from crimping drum 2 of the fence machine passes over suitable rollers or sheaves 21, so arranged as to insure for the attendant head room, and thence 85 over a suitable guide roll 22, to one or the other of the spools 20.

Reference to the Denning patent will show a reel consisting of a single spool. And the machine so equipped must in its 90 operation be intermittent; the machine must stop and remain at rest while a spool upon which a length of fence has been coiled is removed and replaced by another empty spool. By using two spools, it is necessary 95 to interrupt the continuous operation of the machine long enough only to cut away from the filled spool the continuous web advancing from the machine and to secure the severed end to the empty spool standing ready. 100 Then, as the operation proceeds, the filled spool may be removed and replaced by another empty spool, and it will stand ready to serve when the then active spool is filled.

It is not necessary to pause upon the particular construction of the spool, further than to remark that, as shown in Fig. III, each 110

spool includes a core composed of two semi-cylindrical parts capable of being expanded and collapsed again to serve two purposes: first, to removably secure the core in its 5 heads or end-pieces; and, second, to permit of retraction of the core from the roll of fence built up upon it. It is the core portion of the spool only which in this instance is removable, to accomplish the ends 10 described above. Spools of this construction are well known, and no further description of them is requisite.

The spools when in operation are of course positively rotated, and, to the end that each 15 in turn may be stopped and started at the will of the operator, I have invented a clutch mechanism which I shall now particularly describe. The shafts 23 of the spools 20 carry each a sleeve member 24 which, but 20 for the clutch mechanism, turns idly upon it. The two sleeves are connected to turn in unison, by means of a belt 25 traveling on suitable pulleys with which the two sleeves are equipped. One of the said sleeves is 25 further provided with a sprocket wheel 26, through which rotation may be imparted to these two sleeves. Spring-backed clutch members 27, one splined to each of the two shafts 23, advance when released by their 30 controlling levers 28 to make toothed contact with the sleeves 24, and, according as one clutch or the other is so closed, the corresponding spool is rotated. Thus, as will be apparent, the starting and stopping of 35 the spools separately is a matter wholly under the control of the attendant. A tightener 29 for the belt 25 is shown, operable by the hand lever 30.

Driving power may be imparted through 40 the sprocket wheel 26 from any desired source—conveniently from the same source with the machine itself, for under such condition coördination of speed may be the more readily effected; furthermore, any known 45 expedient may be resorted to, to cause the speed of turning of the spool to diminish as the coil of finished fence is built up upon it, for, of course, given a uniformly turning crimping drum, uniform speed of the surface upon which the web of fence is 50 progressively wound, is desirable. In Fig. I of the drawings a source of power for driving the reel is indicated in a shaft 31 between which and the shaft of the reel

suitable driving connection may be made, 55 as by a sprocket wheel 32 and a sprocket chain 33 which as will be understood may be made to engage the sprocket wheel 26 of Fig. II.

As explained at the outset, this reel is applicable to fence machines generally. Details of structure may of course be varied without departing from the invention defined in the ensuing claims. In respect to such matters, the showing of the specification is exemplary.

I claim as my invention:

1. In a wire-fence machine, in combination with machine parts delivering a web of completed fence in continuous length, a reel 70 including a plurality of rotatable cores, removable each from the reel, a source of power, rotation-imparting connection from said source of power to each of said cores, and means for interrupting and making continuous again at will the connection to either 75 of the said cores, substantially as described.

2. In a wire-fence machine, in combination with machine parts delivering a web of completed fence in continuous length, a reel 80 including two rotatable and collapsible cores, securable in or removable from said reel according as they are in expanded or collapsed condition, a source of power, rotation-imparting connection from said 85 source of power to each of said cores, and means for interrupting and making continuous again at will the connection to either of the said cores, substantially as described.

3. In a wire-fence machine a reel for the 90 finished product including a plurality of shafts arranged in parallel position and mounted for rotation, a fence-receiving core 95 removably secured to each shaft and adapted to be rotated thereby, a sleeve rotatably mounted upon each of said shafts, means for rotating said sleeves constantly and in unison, a clutch member splined to each of said shafts and movable longitudinally thereon to make and break driving connection with 100 said sleeves, and means for shifting said clutch members, substantially as described.

In testimony whereof I have hereunto set my hand.

JOHN A. HOLMQUIST.
